ASSEMBLED PACKAGE OF CONTAINERS

Ralph E. Dykes, 315 2nd St., Saddle Brook, N.J. 07662,
and Robert M. Mitchell, 22 Beechwood Road, South
Norwalk, Conn. 06854

Continuation of design application Ser. No. 75,504, June
24, 1963. This application June 20, 1966, Ser. No. 2,729

Term of patent 14 years

(Cl. D58—2)

FIG. 1

FIG. 2

FIG. 3

FIG. 1 is a perspective view of an assembled package of containers, showing our new design;

FIG. 2 is a perspective view thereof from a different angle than the view of FIG. 1; and

FIG. 3 is a perspective view thereof when rotated upwardly approximately 90° from the position thereof in FIG. 2.

In the drawing, the broken lines indicate the outline of a transparent receptacle enclosing the package.

The essential features of our design are shown in full lines and reside in the particular arrangement of four tetrahedral container units cubically packaged, whereby the interface of adjacent units which abut a pair of diagonally opposite corners defines a diagonal line running between the other pair of diagonally opposite corners on each of four adjacent faces of the cubical package, and whereby each of the remaining two faces of the cubical package comprises the base of a pyramidal, pentahedral void, all as shown.

This application is a continuation of our application Ser. No. D.75,504, filed June 24, 1964, entitled "Pack of Assembled Containers," and now abandoned.

We claim:

The ornamental design for an assembled package of containers, substantially as shown and described.
